UNITED STATES PATENT OFFICE

123,779

DESIGN FOR A COMBINED GRATER AND SLICER

Clara Daggett Houser, Mount Jewett, Pa.

Application July 5, 1940, Serial No. 93,582

Term of patent 3½ years

To all whom it may concern:

Be it known that I, Clara Daggett Houser, a citizen of the United States, residing at Mount Jewett, in the county of McKean and State of Pennsylvania, have invented a new, original, and ornamental Design for a Combined Grater and Slicer, of which the following is a specification, reference being had to the accompanying drawing, forming a part thereof, in which;

Fig. 1 is a top plan view of a combined grater and slicer, showing my design.

Fig. 2 is a sectional view of the same taken on the line 2—2 of Fig. 1.

I claim:

The ornamental design for a combined grater and slicer, as shown.

CLARA DAGGETT HOUSER.
